COMBINATION HF-TREATING-CATALYTIC
CRACKING PROCESS

Arthur P. Lien, Hammond, Ind., and Bernard L. Evering, Chicago, Ill., assignors to Standard Oil Company, Chicago, Ill., a corporation of Indiana

Application December 23, 1946, Serial No. 718,038

3 Claims. (Cl. 196—14.11)

1

This invention relates to a process of producing high quality motor fuel from heavier-than-gasoline hydrocarbons by a new and improved combination of HF treating and catalytic cracking and it pertains more particularly to processes wherein the catalytic cracking is effected by silica-alumina type catalysts which are activatable by small amounts of HF.

An object of the invention is to provide a method and means for obtaining maximum yields of high quality motor fuel from catalytic cracking charging stocks containing large amounts of sulfur compounds, objectionable polycyclic hydrocarbons, and/or other components which are not efficiently handled by catalytic cracking processes and/or which may be detrimental in catalytic cracking systems. A further object is to improve the effectiveness and efficiency of catalytic cracking systems employing silica alumina type catalysts, i. e. to obtain increased motor fuel production, decreased coke formation and superior product quality. A still further object is to provide a process wherein the catalyst used in the second step is promoted in situ by traces of treating agent employed in the first step so that the expense of removing such traces of treating agent is largely avoided so that the combination of steps produces results heretofore unobtainable in the art. Other objects will be apparent as the detailed description of the invention proceeds.

Briefly, the invention contemplates the production of high quality motor fuel from heavier-than-gasoline charging stocks which have heretofore presented serious problems to the refining industry. For example, a West Texas gas oil may contain 2 to 3% of sulfur and when such gas oil is charged to a conventional catalytic cracking process the finished gasoline will contain about .3% sulfur and the catalytic gas oil about 1½ to 2% of sulfur. By giving gas oil a preliminary treatment with HF and then subjecting it to substantially the same conditions of catalytic cracking, we obtain a marked and substantial increase in gasoline production per pass and a marked improvement in gasoline quality, the gasoline containing only about one-tenth as much sulfur and being characterized by a higher A. P. I. gravity, a lower bromine number, and a greatly increased responsiveness to lead tetraethyl. In spite of treating losses in the initial step the overall yield of gasoline may be as high as the yield that would be obtained from untreated charging stock. The effective catalytic cracking capacity is markedly in-

creased. The treating step itself eliminates sulfur and other undesirable components and it may produce a utilizable by-product tar from material which would otherwise be deposited as coke on the catalyst in the cracking step. Furthermore, the treating step may remove organic and/or inorganic material from the charge that would otherwise contaminate or deactivate the catalyst and lead to lower conversion, undesirable product distribution, excessive gas and coke formation, etc.

The initial step of the process is a light treatment with HF, i. e. a treatment under such mild conditions as to avoid any substantial amount of cracking but which is sufficient to eliminate the bulk of the sulfur and other undesirable components in the gas oil. In this treating step a relatively large amount of HF, e. g. about 20 to 200% by volume based on charge may be employed at a relatively low temperature of about 50 to 150° F. but preferably about 80 to 100° F. and with a time of contact of the order of about 5 minutes to an hour or more. The treated charging stock may be separated from gases and from the bulk of HF in a settling zone wherein the undesirable polycyclic hydrocarbons and sulfur compounds are withdrawn in the bottom HF layer and gases flashed overhead. The dissolved HF in the treated charge may be partially removed by a simple stripping operation. The treated charge which contains traces of HF is then directly introduced into a catalytic cracking reactor containing a solid catalyst of the silica alumina type and operated under conditions for converting the charge to motor fuel. The traces of HF remaining in this charging stock apparently effect an in situ activation of the cracking catalyst so that the yields per pass of gasoline are substantially increased. The net result of the combined process is the production of remarkably high quality gasoline of low sulfur content, an increase in the capacity of the cracking unit, the substantial elimination of the expense of defluorinating and a net increase in production of valuable by-product materials, the increase in gasoline production made possible by the treating step substantially balancing "losses" of by-product production in the treating step.

The invention will be more clearly understood from the following description read in conjunction with the following drawing which is a schematic flow diagram illustrating a practical application of our invention.

While the invention is applicable to any heavier-than-gasoline hydrocarbon charging

2

stock which contains components such as large amounts of sulfur and/or other components which are deleterious to or are ineffectively handled in a catalytic cracking system, it will first be described in connection with the handling of a heavy West Texas gas oil. This gas oil was treated with HF at room temperature in four successive stages with fresh HF, using in each stage about 1 volume of HF to 5 volumes of charging stock. In each treatment the HF charging stock mixture was vigorously agitated with a 1725 R. P. M. mechanical stirrer for a period of 30 minutes and the HF was then separated by simple settling from the treated charge. At the end of the first stage the percent of sulfur had been reduced from 2.13 to 1.16% with a treating loss of about 18.5 weight percent. By the end of the fourth stage the sulfur content had been reduced to .65% and the total cumulative treating loss was 22.5 weight percent. Inspections of the West Texas gas oil before and after the HF treating steps are as follows:

Representative samples of the gas oil charge and the HF extracted gas oil respectively were catalytically cracked in a fixed-bed unit with Super Filtrol under substantially the same conditions employing a temperature of 910° F. Super Filtrol is the trade name for acid-treated bentonite clay, the principal constituent of which is the clay mineral, Montmorillonite. A comparison of the products obtained is set forth in the following table:

Products from:

From the above data it will be seen that the HF treated gas oil gave less dry gas and coke but

more butane, pentane and gasoline than the untreated gas oil charge. The treated gas oil gave a lower yield of ethane and a higher yield of propylene. Gasoline from the HF treated gas oil contained only about one-tenth as much sulfur as that from the treated gas oil. The lower density, lower bromine number and lower refractive index of gasoline from the HF treated gas oil all indicate a lower olefin content and perhaps a lower aromatic content than that obtained from the untreated feed. An unexpected result is the fact that the cycle stock from the HF treated gas oil actually shows an increase in sulfur content over the charging stock to the cracking step. It may therefore be desirable to subject the cycle stock to the HF treating step before it is returned to the cracking step. The lower density and lower refractive index of the cycle stock from the HF treated gas oil charge indicate lower aromaticity, indicating that the cycle stock is less refractory than the cycle stock from the cracking of untreated gas oil. From a series of studies from which the above data were obtained it was shown that with a given amount of catalyst the HF treated gas oil gives higher conversion with lower coke formation. It is also indicated that at the same conversion level the HF treated gas oil requires markedly less catalyst and produces only about half as much coke, and that at the same coke level the HF treated gas oil gives remarkably higher conversion. In spite of the 22.3% treating losses in the HF treating step, the total converted product will be about the same as from a given amount of original feed, a considerable advantage accruing to the fact that the cycle stock from the treated feed is less refractory than that from the untreated feed.

As a second example, a lower boiling West Texas gas oil was treated on a pilot plant scale with HF under conditions of counter-current extraction with a continuous acid phase at a temperature of 100° F. and with 20.4 volume percent HF, based on hydrocarbon. The following tabulation shows the inspections of the original gas oil as compared with the treated gas oil:

These two stock were then separately cracked in a pilot plant "fluid" catalytic cracking unit. Cracking was carried out with a Super Filtrol catalyst of high iron content under substantially the same conditions for unextracted and extracted charge stocks using a temperature of about 900° F. and a space velocity (Wt. of oil per hour per wt. of catalyst in the reactor) of about

Although the coke formation was unduly high in both cases due to the particular catalyst employed, the markedly lower coke formation in the case of the HF treated charge is noteworthy along with the other indicated improvements in over-all results.

A commercial system for practicing our invention is illustrated in the drawing and our invention will now be described in connection therewith. Charging stock which may be West Texas gas oil, reduced crude or any other heavier-than-gasoline hydrocarbon containing objectionable components, is introduced through line 10 by pump 11 to line 12 where it meets HF from storage tank 13, line 14 and pump 15. Knothole mixers or other mixing means may be employed for attaining intimate contact of the two streams in line 12 and/or said intimate contact may be obtained in treating chamber 16 by mechanical stirrer 17 driven by motor 18. It should be understood that instead of a stirred reactor we may employ a packed or unpacked tower with mixing orifices, a circulating system of the type commonly employed for effecting sulfuric acid alkylation or any other effective contacting means. Instead of the illustrated concurrent flow through the reactor the HF may be introduced at the top thereof while the charge is introduced at the base, such countercurrent treatment being particularly desirable in towers where the treating is to be effected in a countercurrent manner and the separation is effected in the tower itself, the treated material being in that case taken overhead while the HF and impurities are withdrawn from the base of the tower. In the system illustrated in the drawing a mixture of HF and treated charging stock is introduced by line 19 to settler 20, a cooler 21 being employed if the treating is at very high temperature.

The treating should be effected under relatively mild conditions so that sulfur and/or other undesirable components may be removed from the charging stock without materially changing its boiling range, i. e. without effecting substantial amounts of cracking. The treating may be effected at room temperature with about 10 to 200% by volume of HF and any number of stages may be employed in the treating step (although only one stage is shown in the drawing). When it is desired to remove the sulfur compounds as materials soluble in HF the treating should be in the range of 50 to 150° F. The pressure in all cases should be sufficient to maintain the HF in liquid phase.

In settler 20, which may operate at about cooling water temperature, the treated hydrocarbons separate as an upper layer and they may be withdrawn through line 22 to gas oil stripper 23. Settler 20 may, however, operate at higher temperature and in such cases the treated gas oil

6

may be withdrawn through cooler 24 and cold settler 25 for throwing out additional amounts of HF which may thus be recycled directly by line 26, thereby diminishing the load on the stripper tower 23.

- 5 The HF layer from settler 20 is withdrawn through line 27 and recycled to treater 16 via line 12. At least a part of the HF tar in line 27 is directed through line 27-a to tar stripper 28 which is provided at its base with conventional heater or reboiler 29. The tar and sulfur adducts with HF are decomposed by heating to 250-500° F. The overhead from this stripper is passed through condenser 30 to settler 31 in which the 15 HF separates out as a lower liquid and is withdrawn through line 32 to storage tank 13. The upper layer in settler 31 consists of light hydrocarbons and it may be recycled through line 33 by pump 34 to serve as a stripping oil in tower 20 by virtue of azeotrope formation with HF, any deficiency or excess of light hydrocarbons being supplied to or removed from this circulating system through line 35. Tar and sulfur compounds are withdrawn from the base of the stripper 25 through line 28-a and such tar may be utilized per se as a by-product or it may be subjected to coking or cracking (for example with HF) to form additional amounts of gasoline. By heating the materials discharged from settler 20 in a 30 heating zone (not shown in the drawing), to a cracking temperature of about 250 to 500° F. and allowing sufficient time of contact which may be about 10 minutes to an hour or more, much of the tar can be converted into gas oil and/or lighter hydrocarbons before its introduction into stripper 28 and in this case the gasoline components may be recovered in a suitable fractionation system (not shown) or introduced by line 35 to supplement the treated gas oil stream.
- 35 40 If the HF treating is effected at sufficiently high temperature to convert sulfur compounds into H₂S, gases may be removed from the top of the settler 20 through line 36 to knock-back tower 37 which is provided with cooling, scrubbing or reflux means 38 so that methane, H₂S, HCl (from desalting) and other fixed gases may be vented through line 39 while HF and condensable hydrocarbons are returned by line 40 to stripper 23.
- 45 50 Stripper 23 is provided with suitable heater or reboiler 41 at its base and overhead from this stripper passes through condenser 42 to settler 43. Liquid HF accumulates in the bottom of 55 this settler and is withdrawn through line 44 to storage tank 13. A light hydrocarbon is withdrawn from the upper part of the settler through line 45 and recycled by pump 46 to serve as a stripping gas in tower 23, any excess or deficiency of such light hydrocarbons being removed 60 from or supplied to the system through line 47.
- 55 65 The stripped gas oil leaving the base of stripper 23 through line 48 may pass through a pre-heater 49, then pick up hot regenerated catalyst from the base of standpipe 50 and carry this catalyst into reactor 51. Spent catalyst from reactor 51 passes downwardly through standpipe 52, is picked up by air introduced in line 53 and conveyed thereby in line 54 to regenerator 55, regeneration gases being vented through line 55-a. The fluid type catalytic cracking system thus 70 briefly and diagrammatically represented is now well known to those skilled in the art and requires no detailed description. The catalyst-to-oil ratios employed may be in the range of 2:1 to 20:1

on a weight basis, the cracking temperature may be in the range of about 800 to 1000° F. e. g. about 900° F. and the weight space velocity may be in the range of about 0.2 to 20 pounds of oil charged per hour per pound of catalyst in the reactor. In other words, the cracking conditions may be approximately the same as those heretofore employed for conventional gas oil stocks although somewhat smaller amounts of catalyst or higher throughputs may be obtained by virtue of the promoting effect of the residual amounts of HF which are introduced into the cracking system with the treated gas oil. While the fluid type catalytic cracking system has been illustrated in the drawing it should be understood that the invention is equally applicable to fixed bed systems and to moving bed systems. The catalyst itself is of the silica alumina type and may be either conventional Super Filtral or a synthetic silica alumina catalyst of any type known to the art.

Apparently Super Filtral and other silica alumina type cracking catalysts generally are markedly improved in their activity by treatment with HF which perhaps results in the formation of aluminum fluosilicate. In our process this activation of the catalyst is particularly effective because it is produced in situ. The traces of HF remaining in the treated gas oil are thus effectively removed therefrom in the cracking operation and at the same time the effectiveness of the catalyst is increased so that higher conversions per pass are obtained with smaller amounts of carbon deposition on the catalyst. Usually the amount of HF introduced is so small that the make-up catalyst requirements in the cracking step are sufficient to take care of it. In some cases, however, it may be necessary or desirable to pass a portion of the treated gas oil through bauxite chambers or other HF removal means 56 (note U. S. Patent 2,391,149). Our invention minimizes the required HF removal and may entirely eliminate it.

The products from catalytic cracking reactor 51 pass by line 57 to tower 58 which may be provided with a settling section 59 at its base so that catalyst slurry may be returned through line 60 to the stream entering the reactor and decanted oil may be withdrawn through line 61 and either removed from the system or recycled lines 62 and 12 to the HF treating step. Heavy gas oil may be withdrawn as a side stream through line 63, recycled by lines 64 and 12 to the HF treating step, and/or recycled by lines 64 and 64a to the catalytic cracking step. Cycle gas oil from this process is usually in most respects superior to the untreated original gas oil charge but if all of it is recycled through line 64a a buildup in sulfur compounds or aromatics might result; at least a part of the gas oil stream should usually therefore either be withdrawn through line 63 or recycled through line 12 to the treating step in order to prevent any buildup of sulfur compounds or aromatics in the catalytic cracking step. A light gas oil stream may be withdrawn through line 65 and it likewise may be recycled either to the HF treating step or to the catalytic cracking step. Gasoline and lighter components are taken overhead through line 66 and condenser 67 to settler 68 from which any water from diluent steam in the cracking step or otherwise accumulated in the system may be withdrawn through 69. Any gasoline produced in the HF treating or tar cracking and taken overhead from strippers 23 or 28 may be passed via lines 35 or 47 through line 10, HF removal chambers 71 and line

72 to separator 68. Gases from this separator are compressed by compressor 73, liquid hydrocarbons are pumped by pump 74, and the combined stream is passed through line 75 to superatmospheric pressure fractionation system diagrammatically illustrated by tower 76 from which heavy naphtha is withdrawn through line 77, light naphtha through line 78 and one or more lighter naphtha streams through lines 78 and 79. A C₄ or C₃-C₄ stream may be withdrawn through line 80 and such butane or propane-butane mixtures may be introduced by line 81 and line 70 to supply any deficiency of stripping gas for towers 23 and 28 respectively. Dry gas is removed from the system through line 82. In actual practice of course a conventional absorber and stripper system may be employed instead of a simple tower but since this fractionation step per se forms no part of the claimed invention it will not be described in further detail.

From the above description it will be seen that we have accomplished the objects of our invention. The mild HF treating step removes sulfur compounds and/or polycyclic aromatics which are not readily amenable to cracking and makes possible the recovery of tar and sulfur compounds as utilizable by-products. This particular method of pretreating the catalytic cracking charging stock (coupled perhaps with traces of HF left in the treated charging stock) results in greatly increased cracking yields, substantially less carbon formation on the catalyst and an improved cracked gasoline which is less olefinic, more amenable to improvement by lead tetraethyl and which contains only about one-tenth as much sulfur as would be obtained by the cracking of the same stock without the initial treating step. The catalytic cracking apparently concentrates the sulfur compounds in the cycle gas oil so that when this gas oil is recycled to the HF treating step still further amounts of sulfur can be eliminated from the system and kept out of the final gasoline products. The butane or propane-butane hydrocarbons produced in the catalytic cracking step serve as stripping gases and form HF azeotropes which facilitate HF removal from the treated gas oil and the tar respectively. Thus this new and improved unitary combination accomplishes results which have heretofore been unattainable in the cracking of low grade charging stocks and particularly those containing large amounts of sulfur.

The step per se of removing certain polycyclic aromatics by chemical condensation is claimed in our copending application Ser. No. 135,166, filed December 27, 1949, which in turn was a continuation-in-part of copending application Ser. No. 760,061, filed July 10, 1947. The combination process of effecting chemical condensation by use of HF at temperatures in the range of 150 to 400° F. for removing certain polycyclic aromatics prior to catalytic cracking with solid catalysts such as silica alumina type catalysts is claimed in our copending application Ser. No. 168,112, filed June 14, 1950, as a continuation-in-part of the present application and also as a continuation-in-part of our copending application Ser. No. 760,062.

While we have described in detail a specific example of our invention, many alternative modifications, procedures and operating conditions will be apparent from the above description by those skilled in the art. When salt bearing reduced crudes are employed the process will offer the additional advantage of salt removal. No specific details as to structural materials and gen-

eral safety precautions have been recited herein, since those skilled in the art are familiar with the handling of HF in view of its commercial utilization in effecting alkylation.

We claim:

1. In a process for converting a gas oil charging stock containing sulfur compounds and polycyclic aromatic hydrocarbons to low sulfur gasoline while minimizing coke formation by a combination of steps comprising selective extraction of said sulfur compounds and polycyclic aromatic hydrocarbons from said gas oil charging stock and cracking conversion of the resultant purified gas oil with a silica-alumina type catalyst, the steps consisting essentially of contacting said gas oil charging stock with between about 0.1 and about 2 volumes of liquid hydrogen fluoride per volume of said charging stock at a temperature between about 50° F. and about 150° F., stratifying the mixture resulting from said contacting into a hydrogen fluoride solution of organic sulfur compounds and polycyclic aromatic hydrocarbons and a hydrogen fluoride-immiscible layer of purified gas oil of substantially reduced sulfur and polycyclic aromatic hydrocarbon content, said purified gas oil having substantially the same 10 percent to 80 percent distillation temperatures as said charging stock, a substantially reduced carbon residue and containing sulfur compounds which are not readily adsorbed on silica-alumina catalyst during said cracking conversion.

2. The process of converting a gas oil charging stock containing sulfur compounds and polycyclic aromatic hydrocarbons to low sulfur gasoline while minimizing coke formation, which process consists essentially of contacting said charging stock with between about 0.1 and about 2 volumes of liquid hydrogen fluoride per volume of said charging stock at a temperature between about 50° F. and about 150° F., stratifying the mixture resulting from said contacting into a hydrogen fluoride solution of organic sulfur compounds and polycyclic aromatic hydrocarbons and a hydrogen fluoride-immiscible layer of purified gas oil of substantially reduced sulfur and polycyclic aromatic hydrocarbon content, said purified gas oil having substantially the same 10 percent to 80 percent distillation temperatures as said charging stock, converting said purified gas oil with a silica-alumina type cracking catalyst at a temperature between about 800° F. and about 1000° F., fractionating the conversion products into a low sulfur gasoline fraction and a high sulfur cracked gas oil fraction, said cracked gas oil fraction having a higher sulfur content than said purified gas oil, recycling at least a part of said cracked gas oil fraction to a hydrogen fluo-

ride liquid-liquid contacting step, and reducing the sulfur content of said cracked gas oil fraction in the last-named contacting step to a value not greater than that of said purified gas oil.

3. The process of converting a gas oil charging stock containing sulfur compounds and polycyclic aromatic hydrocarbons to low sulfur gasoline while minimizing coke formation, which process consists essentially of contacting said charging stock with between about 0.1 and about 2 volumes of liquid hydrogen fluoride per volume of said charging stock at a temperature between about 50° F. and about 150° F., stratifying the mixture resulting from said contacting into a hydrogen fluoride solution of organic sulfur compounds and polycyclic aromatic hydrocarbons and a hydrogen fluoride-immiscible layer of purified gas oil of substantially reduced sulfur and polycyclic aromatic hydrocarbon content, said purified gas oil having substantially the same 10 percent to 80 percent distillation temperatures as said charging stock, converting said purified gas oil with a silica-alumina type cracking catalyst at a temperature between about 800° F. and about 1000° F., fractionating the conversion products into a low sulfur gasoline fraction and a high sulfur cracked gas oil fraction, said cracked gas oil fraction having a higher sulfur content than said purified gas oil, and contacting said cracked gas oil with between about 0.1 and about 2 volumes of liquid hydrogen fluoride per volume of said cracked gas oil at a temperature between about 50° F. and about 150° F. to produce a gas oil having a sulfur content not greater than that of said purified gas oil.

Certificate of Correction

Patent No. 2,525,812

October 17, 1950

ARTHUR P. LIEN ET AL.

It is hereby certified that error appears in the printed specification of the above numbered patent requiring correction as follows:

Column 3, in the table headed "Products from", column 1 thereof, under "Dry Gas", fifth chemical formula, for "C₂H₆" read C₂H₆; column 4, line 10, for "lawer" read *lower*; line 19, for "terated" read *treated*; column 7, line 49, after "recycled" insert *through*; column 9, line 30, after "silica-alumina" insert *type*;

and that the said Letters Patent should be read as corrected above, so that the same may conform to the record of the case in the Patent Office.

Signed and sealed this 26th day of December, A. D. 1950.
